(57) **CLAIM**

We claim the ornamental design for a model vehicle tire, as shown and described.

DESCRIPTION

FIG. 1 is an upper, right, front perspective view of a model vehicle tire showing our new design;

FIG. 2 is an upper, right, rear perspective view thereof;

FIG. 3 is a front side elevation view thereof;

FIG. 4 is a rear side elevation view thereof;

FIG. 5 is a right elevation view thereof;

FIG. 6 is a left elevation view thereof;

FIG. 7 is an upper plan view thereof; and,

FIG. 8 is a lower plan view of the model vehicle tire.

In the drawings, the broken lines defining the sidewall and inner bead represent unclaimed subject matter that forms no part of the claimed design. The dash-dot-dash broken line represents the peripheral boundary between the claimed design and unclaimed subject matter.
